UNITED STATES PATENT OFFICE.

KOBY KOHN, OF NEW YORK, N. Y.

TOY TORPEDO.

Application filed July 14, 1926, Serial No. 122,466. Renewed April 11, 1928.

This invention relates to toy torpedoes and more particularly to a form of toy torpedo rendered safe by having no freely movable detonating elements.

5 The general object of the present invention is to provide a novel and improved safety form of toy torpedo.

More particularly it is an object of the invention to render the present type of toy 10 torpedo safe and prevent premature explosion of the same by fixing the gravel or other detonating elements to one or more walls of the explosive container.

A further object of the present invention 15 consists in the provision, in a toy torpedo, of an explosive compound, a plurality of granular detonating elements and an enclosing gastight casing, all of the detonating elements being lightly secured to one or 20 more interior walls of the casing, so that they can be only separated therefrom upon impact of the torpedo against a hard surface.

A still further object of the present invention 25 consists in the provision of a novel and improved method of securing gravel or other detonating means in a toy torpedo to the walls of the explosive container.

Other and further objects of the invention 30 will be more apparent, to those skilled in the art, by reference to the accompanying drawing and following specification, wherein is disclosed a single exemplary embodiment of the invention, it being understood, however, 35 that various changes may be made therein without departing from the spirit of the invention or the scope of the appended claims.

In said drawing:

Figure 1 is a perspective view of a completed torpedo constructed according to the 40 present invention;

Figure 2 is a vertical central section of the container before the gravel is applied; and

45 Figure 3 is a vertical central section of the completed torpedo.

The present and most popular types of toy torpedoes are either of tubular or globular construction. In either type it is customary 50 to have a container in which are placed an explosive composition, and detonating or abrasive means for setting off the explosive. The latter is usually gravel, or similar material, which is placed together with the explosive within the container, which is sealed

to make it gastight. The container may or may not be provided with suitable reinforcing means placed about its exterior to increase its bursting resistance and hence the intensity of the report when the explosive is detonated by impacting the torpedo against a hard surface. The gravel and explosive do not tightly fill the container and can move about freely, so that it frequently happens that sufficient percussion or impact between the gravel particles and the explosive is caused by slight jars incident to shipping and storing the torpedoes to cause the explosion of one of the torpedoes. This explosion may be immediately transmitted to adjacent torpedoes so that a whole case and even a whole carload may be exploded simultaneously, resulting in great property damage and physical injury to those near by. The present invention contemplates securing the gravel in position against accidental movement until the torpedo is subject to intentional impact.

Referring to the drawing, there is shown at 10 a section of tube which is formed of some tenacious material such as cardboard or the like and preferably, though not necessarily, circular in cross-section. In some instances this tube may form the exterior of the torpedo, but it is usually covered either 15 for decorative purposes or to increase its resistance to bursting, and is sometimes rolled in a mixture of an agglutinant and some material such as wood-flour to cause it to assume a spherical shape, the latter 20 operation, however, taking place after the charge has been placed and sealed within the tube.

The inner wall of the tube is lined with a suitable adhesive or mastic for a purpose 25 to be later described. This material is applied in a thin layer around the inner wall of the tube, as shown at 11 in Figs. 2 and 3. After this adhesive or mastic has been applied to the wall of the tube, a suitable closure 12 is applied to the bottom of the tube. It may consist of a cardboard disk or the like pressed inside the open end of the tube and may be secured by a suitable adhesive or by that already within the tube.

It is preferred to use pitch or a similar mastic material for the coating 11. This material is applied in a hot state to the inner walls of the tube. In actual manufacture a plurality of the tubes in the condition shown

in Fig. 2 are grouped in trays to receive the gravel or other detonating means. Gravel is the most common material, but it is to be understood that the word "gravel" herein-
5 after used refers to any suitable detonating or abrading medium. The gravel is heated to a temperature sufficiently high to cause it to melt the pitch and it is poured into the tubes until they are filled. It melts the pitch
10 and a number of particles or granules adhere to the pitch, as shown at 13 in Fig. 3. When the gravel and pitch have cooled sufficiently, the tubes are inverted and the gravel which has not stuck to the walls of the tubes is
15 shaken out for future use. This leaves a cuplike container having a smooth bottom and walls lined with gravel which sticks but lightly thereto by virtue of the proper temperature given to the gravel when it is filled
20 into the cups so that it sinks but little into the pitch. The pitch mastic is of such a composition that it is relatively brittle, so that upon considerable impact the gravel will be shaken or broken loose and the particles
25 will come together with considerable force. If sufficient pitch is used there may be a second or inner layer of gravel adhering to the pitch which squeezes between the gran-
30 ules of the first layer. This layer reduces the diameter of the "bore" of the tube and al-
lows the gravel granules to come together more readily when the torpedo is impacted.
The tubes with the gravel secured to the walls are next filled with a suitable explo-
35 sive composition 14, such as chlorate of po-
tassium, antimony and sulfur. After a suf-
ficient quantity of explosive has been placed in the containers, they are each provided with a sealing closure or cap 15 secured in posi-
40 tion in any suitable manner.

In case it is desirable to use an adhesive instead of the mastic pitch, some such quick drying adhesive as shellac, collodion or the like may be applied to the interior of the
45 cup or container and the gravel immediately placed therein. This, in contacting with the adhesive, will adhere to the walls of the tube, and after the adhesive has set, the loose sur-
plus gravel is shaken from the container. It
50 will be seen that by applying the mastic or adhesive to the proper thickness on the walls of the tube and by having it of the proper consistency, the gravel can be adequately re-
tained in position against accidental dis-
55 placement and yet can be readily broken loose so that the granules thereof may con-
tact with each other and cause the explosive compound to be detonated when the torpedo is thrown sufficiently hard against a solid
60 surface.

Having thus described the invention, what

is claimed as new and desired to be secured by Letters Patents is:

1. In a toy torpedo, in combination, a gas-
tight container, an explosive composition 65
within said container, an adhesive coating
on an interior wall of said container, and
abrasive material secured to said wall by said
coating.

2. In a toy torpedo, in combination, a gas-
tight container of tenacious material, an ex-
plosive composition within said container,
and a plurality of percussion elements light-
ly secured to an interior wall of said con-
tainer.

3. In a toy torpedo of the type adapted
to be exploded by impact, in combination,
an explosive composition, granular percu-
ssion material, a gastight container complete-
ly enclosing said explosive composition and 80
percussion material, and means weakly se-
curing all of said percussive material to the
interior wall of said container.

4. The method of making a toy torpedo
comprising forming a container having an 85
opening through a wall thereof, applying a
mastic to an inner wall of the container, fill-
ing the container with granular material,
pouring out the granular material not ad-
hering to said mastic, filling explosive mate-
rial in said container and sealing said open-
ing.

5. As a new article of manufacture, a con-
tainer for explosive for a toy torpedo hav-
ing gravel weakly adherent to an inner wall 95
thereof.

6. As a new article of manufacture, a con-
tainer for explosive for a toy torpedo com-
posed of tenacious material and having per-
cussion means secured to a wall thereof.

7. As a new article of manufacture, a tube
forming part of a gastight enclosure for ex-
plosive for a toy torpedo, said tube having
elements lightly secured to the inner wall
adapted to break loose and impact with each
other to detonate explosive material in said
105 container when the torpedo is impacted.

8. As a new article of manufacture, a tube
forming part of a gastight enclosure
for explosive for a toy torpedo, said tube
having a coating of mastic on its inner wall
and granular abrasive material adhering to
said mastic.

9. In a toy torpedo, in combination, a car-
board tube, closures for the ends thereof
forming a compartment, an explosive in said
compartment, adhesive material on the inner
wall of said tube, and coarse gravel adhering
to said inner wall.

In testimony whereof I hereunto affix my
signature.

KOBY KOHN.
